UNITED STATES PATENT OFFICE.

TALMADGE BLASS, OF MILLERTON, NEW YORK, ASSIGNOR TO WILLIAM ANGEVINE AND GEORGE S. FRINK, BOTH OF SAME PLACE.

SUCTION-CONDENSER FOR STEAM-PUMPS.

SPECIFICATION forming part of Letters Patent No. 289,748, dated December 4, 1883.

Application filed June 6, 1883. (No model)

To all whom it may concern:

Be it known that I, TALMADGE BLASS, of Millerton, in the county of Dutchess and State of New York, have invented a new and Improved Suction-Condenser for Steam-Pumps, of which the following is a full, clear, and exact description.

The object of my invention is to provide a new and improved device for condensing the 10 exhaust-steam from any steam pump or engine, so as to relieve the piston from the back-pressure of the exhaust-steam, whereby the quantity of steam required for running the pump and consequently also the expenses are 15 reduced materially.

The invention consists in a pipe surrounding a perforated part of a steam-pump suction-pipe or steam-condenser, and forming a space between the two pipes, into which space 20 the exhaust-steam is conducted, upon which it passes through the perforations into the water and is condensed. The outer pipe is provided with an eccentric steam-channel connected with the steam-inlet pipe, which is 25 provided with an automatically-closing valve.

Reference is to be had to the accompanying drawings, forming part of this specification, in which similar letters of reference indicate corresponding parts in both the figures.

30 Figure 1 is a sectional view of my improved suction-condenser. Fig. 2 is an inverted sectional plan of the same on the line *x x*, Fig. 1.

The suction-pipe A of a steam-pump is provided with a series of perforations, *a*, and 35 the perforated part of the suction-pipe is surrounded by a pipe, B, forming a jacket around the pipe A. The pipe or casing B is provided with an eccentric channel, C, for conducting the exhaust-steam into the space between the 40 pipes A B—that is, the depth of the channel C gradually decreases from the entrance part for the steam to a point diametrically opposite, as shown in Fig. 1. The channel C is provided at its widest part with a neck, D, 45 containing a bushing, D', forming a seating for a puppet-valve, E, mounted on a stem, F, guided in an aperture in the suction-pipe in a spider or cross-piece in the neck. The steam is conducted to the neck D by the exhaust-steam

50 pipe G, which is provided with a three-way cock, H, to permit adjusting the exhaust-steam pipe for exhausting in the air. The condenser is provided with a vacuum-chamber, J, for the purpose of preventing pounding in the suction-pipe. A spiral spring, K, surrounding the stem F, closes the valve E automatically. 55

The operation is as follows: The steam is exhausted into the air until the water rises in the suction-pipe up to the perforated part, and 60 then the steam issues in jets through perforations into the water, and is condensed instantly. The spring K closes the valve after each exhaust of the pump, thus preventing the water from the suction-pipe from rushing into 65 the steam-cylinder of the pump.

The condenser is very simple, and does not occupy much space, as it is only a slight enlargement of the suction-pipe. It does not obstruct the water in the suction-pipe, and operates as well with dirty as with clean water. 70 If desired, the steam of a steam-engine can also be conducted into the condenser.

The condenser can be placed in any desired position.

Having thus described my invention, I claim as new and desire to secure by Letters Patent—

1. The combination, with a suction-pipe having perforations, of the pipe B, surrounding it, and provided with an eccentric channel, C, and of an automatic valve for closing the steam-entrance, substantially as herein shown and described, and for the purpose set forth.

2. The combination, with a suction-pipe having perforations, of the pipe B, surrounding it, and provided with a channel, C, the valve E, the exhaust-pipe G, and the three-way cock H, substantially as herein shown and described, and for the purpose set forth.

3. The combination, with the suction-pipe A, having the perforations *a*, of the pipe B, provided with a steam-inlet, and of a vacuum-chamber, J, substantially as set forth.

TALMADGE BLASS.
